Edwin P.S. Newman

UNITED STATES PATENT OFFICE.

EDWIN P. S. NEWMAN, OF WASHINGTON, DISTRICT OF COLUMBIA, ASSIGNOR OF ONE-HALF TO EDWARD R. WALTON, JR., OF WASHINGTON, DISTRICT OF COLUMBIA.

CARBON-PAPER SHEET.

Application filed June 3, 1924. Serial No. 717,619.

My invention relates to an improvement in carbon paper used for manifold purposes. Paper of this character is usually of very thin stock, and the impression surface 5 comes off on the fingers in the handling of the paper, especially if the hands are at all moist. The thin stock is apt to curl on the edges, and the soiling of the hands affects the neatness of the work. It is the object 10 of my improvement to overcome these defects.

For the accomplishment of this object I provide a carbon sheet with one or more turned over edges, whereby a stiffened edge 15 is provided to prevent curling, and an uncarbonized surface is presented for its manipulation. This is illustrated in the accompanying drawing in which

Figure 1 shows the carbon sheet embodying the invention; and,

Figure 2 shows a cross section.

In the drawing, the sheet of carbon paper, I is shown with one or more turned over edges, 2 and 3 of convenient width. These 25 edges are preferably provided at the top and bottom or transverse portions of the sheet for convenience in handling and to avoid interference with the use of the carbon paper in a typewriting machine. As shown the 30 impression or carbonized surface is folded upon itself thus providing an edge, both surfaces, 5 and 6, of which are uncarbonized. Mere folding of the paper may be sufficient but I prefer to secure the folded portion to 35 the body of the sheet. I have discovered that this may readily be done with carbon paper of usual composition by running a heated surface over the folded portion which causes the juxtaposed carbonized surface to 40 adhere and so bind the paper edge to the body surface. A small degree of heat is all that is usually required, but evidently the carbon composition will dictate whether heat may be used and the degree of heat that 45 is necessary. Suitable adhesives may be

used in the place of heat treatment. By the term carbon paper I include any paper used for manifold purposes.

I claim:

1. A sheet of carbon paper having one surface at one end of the paper uncarbonized and folded over upon the body of the sheet to provide a clean marginal portion at said end of the sheet and on opposite sides thereof.

2. A sheet of paper carbonized on one surface and having its top end portion folded upon itself transversely and upon the carbonized surface thereof, whereby a clean marginal surface is provided at said end of the carbonized surface of the sheet, said folded portion being secured to the body of the sheet and reinforcing the same.

3. A sheet of carbon paper having one surface uncarbonized and being folded at at least one of its edge portions upon the carbonized surface of the sheet to provide a reinforced uncarbonized marginal portion at said edge of the sheet.

4. A sheet of carbon paper having its transverse end portion uncarbonized at least on one surface thereof and folded over upon the sheet to provide a clean marginal portion on opposite sides thereof and at both ends of said sheet.

5. A process of preparing carbon paper having a carbonized surface which comprises folding an edge of the paper upon the carbonized surface and in securing the edge to the body of the paper by the adhesive action of the carbonized surface.

6. A process of preparing carbon paper having a carbonized surface which comprises folding an edge of the paper upon the carbonized surface and in securing the edge to the body of the paper by the adhesive action of the carbonized surface through the application of heat.

In testimony whereof I affix my signature.
E. P. S. NEWMAN.
